ATTORNEY

UNITED STATES PATENT OFFICE.

LOUIS A. ROSENTHAL, OF LOUISVILLE, KENTUCKY.

OVERALLS.

Application filed May 3, 1926. Serial No. 106,406.

My invention relates to improvements in overalls or work garments and has particular reference to means for reinforcing the garment at the side vent, thereby preventing 5 ripping or tearing at the bottom of the side vent.

In accordance with my invention, I provide a continuous strip which is folded about and encloses the edge of the rear body portion of 10 the overall or garment, adjacent to the side vent, and which is stitched thereto. This continuous strip is extended forwardly across the bottom of the side vent and passes upwardly along the rear side of the front 15 body portion of the overall or garment, and is stitched to this front portion, adjacent to the front pocket.

In the accompanying drawings, forming 20 a part of this specification, and in which like numerals are employed to designate like parts throughout the same,

Figure 1 is a fragmentary side elevation of a pair of overalls embodying my invention,

Figure 2 is a similar view, with the side 25 vent partly opened,

Figure 3 is a plan view of the reinforcing strip, applied to the garment,

Figure 4 is a longitudinal section taken on line 4—4 of Figure 1,

Figure 5 is a transverse section taken on line 5—5 of Figure 1,

Figure 6 is a transverse section taken on line 6—6 of Figure 1, and,

Figure 7 is a plan view of the reinforcing 35 strip or blank.

In the drawings, wherein for the purpose of illustration, is shown a preferred embodiment of my invention, the numeral 10 designates the rear portion and the numeral 11 40 the front portion, of the body portion of a pair of overalls or work garment. Arranged between the overlapping edges of the rear and front portions 10 and 11, at each side of the garment, is the usual side vent 12. The 45 front portion 11 carries the usual front pocket 13.

In accordance with my invention, I provide a section of fabric or blank 14, Figure 7, embodying a forward reduced section 15 50 and a rear tapered section 16, which increases in width rearwardly, and these two sections are integral. Both sections 15 and 16 are foldable upon longitudinal lines 17 and 17', and the rear section is foldable, in addition, upon

lines 18 and 19. A notch 20 is cut in the 55 sections 15 and 16, at their points of union, and a shoulder 21 is provided at this point.

In the application of this continuous or integral strip or blank, to the garment, the rear section 16 is first positioned, in an in-

verted relation, upon the inner face of the rear body portion 10, and stitched thereto longitudinally of and adjacent to the line 18, as indicated at 18^a.

This line of stitching 18^a is spaced from the free edge of the rear portion 10. The section 16 is now folded forwardly over the line of stitching 18^a

causing the same to be folded longitudinally upon the line 18. The section 16 is now folded upon the longitudinal line 70

17, which is adjacent to the free edge of the body portion 10, thus producing a face 17^a upon the inner side of the body portion 10 and a face 17^b upon the outer side of the body portion 10. The section 16 is now fold-

ed inwardly along the line 17', producing a strip 17^c, having its inner edge folded upon itself, along the line 19. As clearly shown in

Figure 5, the strip 17^c is arranged between the outer face 17^b and the body portion 10. The folded edge of the face 17^c is preferably 75

stitched longitudinally adjacent to the line 19. The section 16 constitutes a casing or

facing enclosing the edge of the rear body portion 10. The rear section 16, thus folded and 80

applied to the rear body portion 10, is stitched thereto adjacent to its outer edge, as indicated at 22 Figure 6, and the opposite edge

of the section 16 is stitched to the body portion 10 as indicated by the line of stitching 90

23. The line of stitching 22 does not pass through the upper end of the rear section 10, as the rear section 16 tapers upwardly, and the folded reinforcing strip is stitched 95

adjacent to its edge. Hence the stitching 22 is shown passing through the section 10, in Figure 6, and spaced from the edge of the section 10, Figure 5.

The forward section 15 is folded longitudinally upon itself, along the lines 17 and 100

17', producing inner strips 24 and 25. This folded forward section 15 is extended across the bottom of the vent and extends along the inner face of the forward body portion 11, and the upper end of the section 15 is arranged beneath a band 28, secured to the lower end of the bib 29 of the overall, the edge of 105 this bib being folded over the band 28, as

shown at 30. The notch 20 permits of the proper folding of the sections 15 and 16, and the arrangement of the rear section 16 upon the inner and outer sides of the rear body portion, while the folded section 15 is positioned entirely upon the inner side of the front body portion 11. The folded section 15 is stitched at its inner and outer edges, to the front body portion 11, by continuations 10 of the stitches 22 and 23. A transverse tack 30' is preferably provided at the bottom of the vent. I may also secure buttons 31 to the folded section 16 and these buttons are adapted to be inserted within button-holes 32 15 formed upon the front body portion 11.

It is thus seen that I have provided a continuous strip of fabric, which encloses the edge of the rear portion of the garment at the side vent, and this continuous strip extends 20 across the bottom of the side vent and then up the inner face of the front portion. In this manner, the vent is reinforced at the bottom. The front pocket is provided with the usual facing, which terminates at the bottom of the 25 vent.

It is to be understood that the form of my invention, herewith shown and described is to be taken as a preferred example of the same and that various changes in the shape, 30 size and arrangement of parts may be resorted to without departing from the spirit of my invention, or the scope of the subjoined claim.

Having thus described my invention, I claim:

The combination with the front and rear body portions of a pair of overalls or work garment providing a side vent therebetween, of an integral strip embodying a straight front section and a tapered rear section, the rear section having a greater width than the front section and increasing in width away from the same, there being a notch and shoulder at the union of the front and rear sections, the rear section being folded longitudinally about the edge of the rear body portion providing inner and outer faces, the inner face being folded longitudinally adjacent to its longitudinal edge, providing an inner fold which is stitched to the rear body portion beneath the inner face, the outer face being folded longitudinally upon itself and stitched to the rear body portion adjacent the fold, the front section being folded longitudinally at points adjacent to its longitudinal edges and applied to the rear face of the front body portion and stitched thereto through the folded edges of the front section, the folded edges of the front section constituting continuations of the folded edges of that portion of the rear section which is arranged upon the outer face of the rear body portion.

In testimony whereof I affix my signature.

LOUIS A. ROSENTHAL.
